(57) **CLAIM**

I claim the ornamental design for a pineapple shaped drinking vessel, substantially as shown.

DESCRIPTION

FIG. 1 is a perspective view of a pineapple shaped drinking vessel showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan thereof;

FIG. 7 is a bottom plan view;

FIG. 8 is a perspective view thereof with the lid in alternate position;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan thereof; and,

FIG. 14 is a bottom plan view.
